Fig. 1

To all whom it may concern:

Be it known that I, Robert K. Howie, a citizen of the United States, residing at Decatur, in the county of Macon and State of Illinois, have invented a new, original, and ornamental Design for a Fryer Handle, of which the following is a specification, reference being had to the accompanying drawing, forming a part thereof.

I claim:
The ornamental design for a fryer handle, as shown.
